UNITED STATES PATENT OFFICE.

WARNER LULOFS, OF AMSTERDAM, NETHERLANDS, ASSIGNOR TO THE BABCOCK & WILCOX COMPANY, OF BAYONNE, NEW JERSEY, A CORPORATION OF NEW JERSEY.

BOILER FURNACE.

Application filed February 5, 1926, Serial No. 86,163, and in Great Britain July 8, 1925.

My present invention relates to furnaces particularly adapted for use with steam boilers, the walls of which furnaces are provided with devices by which they may be cooled and maintained. My invention will be best understood from the following description and the annexed drawing in which Fig. 1 is a rear elevation of a known form of steam boiler and furnace to which my invention has been applied, portions of the figure being broken away for purpose of illustration; Fig. 2 is an enlarged section on the line 2—2 of Fig. 1, and Fig. 3 is a view similar to Fig. 2 but showing a modification.

Like reference characters indicate like parts in the different views.

The steam boiler which I have chosen for purpose of illustration, is of the water tube type having an upper steam and water drum 10 and the usual water tubes positioned over a furnace chamber.

The furnace chamber illustrated is substantially rectangular in cross-section with its walls diverging from the bottom upward, the furnace, in the illustrative embodiment, being heated by oil burners 11.

In each of the side walls of the furnace is a row of cooling tubes 12, these tubes on two opposite sides of the furnace being connected at their upper ends to a header 13 and at their lower ends to a header 14. The lower headers 14 are connected through pipes 15 to the water space of the drum 10 and the upper headers 13 are connected through pipes 16 to the steam space of the drum 10, or at least at a point higher than the connection of the pipe 16 to the drum 10. In the two remaining sides walls, in the illustrative form, there is an upper header 17 and a lower header 18, the latter being connected at each end to one of the pipes 15 and the upper header being connected by the pipe 19 to the drum 10. The several headers are preferably positioned outside of the furnace wall and the tubes 12 have their ends bent to extend through the wall into the respective headers. The particular means for supplying a cooling medium to the tubes 12 which I have just described is no part of my present invention and further description thereof will be unnecessary to those skilled in the art.

Each of the walls is made up of tile 20 which, in the illustrative embodiment, are

arranged in vertical rows between each pair of tubes 12, as best shown in Fig. 2, with the joint between adjacent rows of tile substantially opposite the tubes 12. The side edges of the tile 20 are recessed, so that when the two rows of tile are in position, as shown in Fig. 2, there will be a relatively large space formed around the pipe 12 with this space closed toward the front or furnace side of the tile and opened at the outer side, the recess preferably being made narrower on its open side than the diameter of the tube 12. The wall preferably is laid up without bond, and it will be noted by an inspection of Fig. 2 that the wall may move in several directions independently of the tubes 12 and, at the same time, no tile 20 can be removed from the wall without spreading a pair of tubes 12 for that purpose.

When the walls are divergent, as shown in Fig. 1, the tile 20 will rest against the tubes 12 so as to form a point contact therewith, as shown in Fig. 2, and this will assist in holding the wall in desired position while, at the same time, leaving it free for expansion and the like.

Outside of the wall formed of the tile 20 is a casing 21 which may be of the usual type or may be made up of another row of refractory, as desired. The space 22 between the casing 21 and the outer faces of the tile 20 forms an air circulation space through which, in the illustrative embodiment, combustion air is drawn by a fan 23 connected to ducts 24 and 25, the lower end of the latter being connected to the upper end of the space 22. The air enters through an opening or openings at the bottom of the casing 21, as best shown in Fig. 1.

It will be seen that with the arrangement described, not only is the wall cooled by the presence of the tubes 12 through which water is circulating, but is also cooled by the air which is drawn through the spaces around the tubes 12, which spaces, in the form illustrated, are extended toward the inner or furnace face of the tile 20 to a point beyond the center of the tile. By the arrangement described, the tile 20 are held in place by the cooling tubes 12 and, at the same time, by reason of the recesses or spaces around the tubes 12, the cooling air is brought close to the furnace side of the tile, so that the tile 20 may be maintained throughout at a closer

approximation to uniform temperature than would otherwise be possible.

In Fig. 3, I have shown a slight modification of the wall in which the tile 20^a have their edges shaped so as to provide substantially circular recesses, each substantially concentric with a tube 12 and furthermore Fig. 3 shows the position of the parts where the wall is vertical and the tiles 20^a therefore have no definite tendency to move against the tubes 12.

I claim:

1. In a furnace, a row of tubes, connections to supply a cooling medium thereto, tile between each pair of adjacent tubes in the row, with the tubes between the inner and outer faces of the tile and with spaces in the tile through which the tubes extend, said spaces being closed as to the inner face of the tile and open as to the outer face, and an outer wall spaced from said tile to form a cooling air passage therebetween.
2. In a furnace, a row of tubes, connections to supply a cooling medium thereto, tile between each pair of adjacent tubes in the row, with the tubes between the inner and outer faces of the tile and with spaces in the tile through which the tubes extend, said spaces being closed as to the inner face of the tile and open as to the outer face, an outer wall spaced from said tile to form a cooling air passage therebetween, and means to circulate cooling air through said passage and through said spaces in the tile.
3. In a furnace, a row of tubes, connections to supply a cooling medium thereto, tile between each pair of adjacent tubes in the row, with the tubes between the inner and outer faces of the tile and with spaces in the tile through which the tubes extend, said spaces being closed as to the inner face of the tile and open as to the outer face, and an outer wall spaced from said tile to form a cooling air passage therebetween, said spaces in the tile extending into the tile for more than half the thickness thereof.
4. In a furnace, a row of vertically disposed tubes inclined outwardly, connections

to supply a cooling medium thereto, tile between each pair of adjacent tubes in the row, 50 with the tubes between the inner and outer faces of the tile and with spaces in the tile through which the tubes extend, said spaces being closed as to the inner face of the tile and open as to the outer face, said tile resting against said tubes, and an outer wall spaced from said tile to form a cooling air passage therebetween.

5. In a furnace, a row of vertically disposed tubes, connections to supply a cooling 60 medium thereto, a vertical row of tile between each adjacent pair of tubes, with recesses in their sides to form, with the recesses in the adjacent rows of tile, spaces surrounding the tubes, and with said spaces closed 65 as to the inner faces of the tile and open as to the outer faces of the tile, and means to circulate air through said spaces and around said tubes.

6. In a furnace, a row of vertically disposed tubes, connections to supply a cooling medium thereto, a vertical row of tile between each adjacent pair of tubes, with recesses in their sides to form, with the recesses in the adjacent rows of tile, spaces 75 surrounding the tubes, and with said spaces closed as to the inner faces of the tile and open as to the outer faces of the tile, and means to circulate air through said spaces and around said tubes, the width of the open 80 ends of said spaces being less than the diameter of the tubes.

7. In a furnace, a row of vertically disposed tubes, connections to supply a cooling medium thereto, a vertical row of tile be- 85 tween each adjacent pair of tubes, with recesses in their sides to form, with the recesses in the adjacent rows of tile, spaces surrounding the tubes, and with said spaces closed as to the inner faces of the tile and open 90 as to the outer faces of the tile, and means to circulate air through said spaces and around said tubes, each of said tubes contacting with the side of one of said spaces nearest the inner face of the tile.

WARNER LULOFS.
